UNITED STATES PATENT OFFICE

125,850

DESIGN FOR A SUIT

Nettie Rosenstein, New York, N. Y.

Application January 2, 1941, Serial No. 97,762

Term of patent 3½ years

To all whom it may concern:

Be it known that I, Nettie Rosenstein, a citizen of the United States, residing at 101 Central Park West, New York city, in the county of New York and State of New York, have invented a new, original, and ornamental Design for a Suit, of which the following is a specification, reference being had to the accompanying drawing, forming part thereof.

I claim:

The ornamental design for a suit, substantially as shown.

NETTIE ROSENSTEIN.
